His Attorney.

UNITED STATES PATENT OFFICE.

HENRY E. WARREN, OF ASHLAND, MASSACHUSETTS, ASSIGNOR TO GENERAL ELECTRIC COMPANY, A CORPORATION OF NEW YORK.

TIMING DEVICE.

1,408,050.

Specification of Letters Patent. Patented Feb. 28, 1922.

Application filed February 3, 1920. Serial No. 356,107.

To all whom it may concern:

Be it known that I, HENRY E. WARREN, a citizen of the United States, residing at Ashland, county of Middlesex, State of 5 Massachusetts, have invented certain new and useful Improvements in Timing Devices, of which the following is a specification.

This invention relates to timing devices 10 and more particularly to a device used for determining very short intervals of time of the order of a fraction of one second, accurately to within say one hundredth of a second.

15 The object of my invention is to provide a device functioning as above stated and making use of the smallest possible number of parts. With my device it is entirely feasible to measure the time to within one hundredth 20 of a second elapsing between any two or more events, such for example as the closure of a switch and the response of a relay thereto.

Broadly considered, my invention 25 comprises a constant speed motor of any well-known type and a shaft rotated thereby carrying one or more wheels frictionally engaging said shaft. Each of said wheels carries means whereby when it is stopped it 30 performs a timing function; or if later another one be stopped the relative movement of the two wheels may be readily determined conveniently in time units.

The construction and mode of operation of 35 an apparatus embodying my invention will be understood from the following description taken in connection with the accompanying drawings, in which Fig. 1 is a view more or less diagrammatic showing the 40 arrangement of the wheels, the means for driving them and the means for stopping their rotation, and Fig. 2 is a section along the line 2-2 looking in the direction of the arrows and showing the arrangement of the 45 means for reading the relative rotation between any two of the disks.

Referring now more in detail to the drawings, in which like reference numerals refer to like parts throughout, the shaft 11 is 50 shown as appropriately geared to a constant speed motor 12; in this case shown as a self-starting synchronous motor of the type referred to in my Letters Patent No. 1,283,433. This motor 12 is supplied from a source of 55 supply 14 of alternating current. The shaft

11 is appropriately supported by stationary members 13. Frictionally engaging said shaft 11 are a plurality of members 15, 15' and 15'' here shown as wheels having a large number of fine notches 16 on their peripheries as clearly shown in Fig. 2. These 60 wheels 15, when not restrained, rotate with the shaft 11. The shaft 11 is so geared that it makes one revolution say in one second. It is quite evident that should one of the 65 wheels, say 15'', be stopped in any manner at one instant and wheel 15' at a later instant; then if there should be some means for determining the relative movement of said two wheels, a correct measure could be 70 had of the length of time elapsing between the stoppage of said wheels.

Any appropriate means may be used for stopping the rotation of the wheels. In this instance the notches 16 and cooperating 75 pawls 17 are utilized. Said pawls are appropriately controlled by electromagnets 18, 19 and 20 energized from an appropriate source of power 21, which latter source of power may or may not be the same as the 80 source 14 for driving the synchronous motor 12. The pawls 17 are adapted to be pulled away from engagement with the notches 16 by means of springs 22. When any one of 85 said electromagnets 18, 19 and 20 are energized, however, the corresponding pawl is moved into engagement with the notches 16 and the wheel with which said pawl cooperates is stopped from rotating. The electromagnets 18, 19 and 20 are made to respond 90 to certain changes in their electric circuits; for example, as shown, to a closing of the circuit. In the drawing a diagrammatic representation is shown of blade switches 23 for performing this change in 95 the circuit, but when the device is actually used it is entirely feasible to have the closure of the circuit depend upon other acts, such for example as the response of a relay to its energizing circuit. Thus, the electromagnet 100 20 may be arranged to be energized when the relay is energized, while electromagnet 19 may be arranged to be energized when the relay contacts close. In order to facilitate the determination of the relative movement 105 of the wheels 15, 15' and 15'', use is made of a calibrated dial 24 marked upon one surface of the disk and a pointer 25 carried by the adjacent disk as clearly shown in Fig. 1. The circular dial 24 may be graduated as 110

shown in hundredths of a second. In this way the relative movement of any two of the disks may be accurately determined. It is evident also that any number of disks may 5 be mounted on shaft 11.

The operation of the device is apparent from the foregoing description. It is only necessary to add that before the device is started, each of the pointers 25 and 26 must 10 be placed on the zero mark of the cooperating dial 24, and that the wheel 15" is the first to be stopped, then the wheel 15' and lastly the wheel 15, assuming rotation in the direction of the arrow in Fig. 2. When determining the length of time it takes a relay 15 to close its contacts, this order of closure is always known. Furthermore, no appreciable error is introduced due to the inertia of the moving parts, because the amount of 20 lag to the response of the closing of the circuit is the same for each of the magnets 18, 19, and 20, so that the errors are compensated. Furthermore, the parts are all made extremely light, so that the lag itself 25 is bound to be very small.

While I have shown in the accompanying drawings the preferred embodiment of my device, my invention is not limited thereto, and I aim in the appended claims to embrace all modifications falling fairly within the scope of my invention.

What I claim as new and desire to secure by Letters Patent of the United States, is:

1. In combination, a shaft, a pair of rotatable members frictionally mounted upon said shaft so as to be driven thereby, means for driving said members at a uniform speed, means for stopping said members at different times, and indicating means carried by said 35 members to indicate their relative movement.

2. In combination, a shaft driven at a uniform speed, a plurality of wheels frictionally mounted upon said shaft so as to be driven thereby, means responsive to the 40

action of electric circuits to control the rotation of said wheels, and means for determining the relative movement of said wheels to each other in time units.

3. In a timing device, a shaft, a constant speed motor for driving said shaft, a plurality of wheels frictionally mounted upon said shaft so as to be driven thereby, said wheels having fine notches on their peripheries, a pawl for each of said wheels adapted 55 to engage with said notches to stop the rotation thereof, electromagnets for actuating said pawls, adapted to be energized in response to changes in an electric circuit, and means comprising pointers and dials 60 for determining the relative movement of said wheels in time units.

4. In a timing device, a shaft, a constant speed motor for driving said shaft, a plurality of wheels frictionally mounted upon 65 said shaft so as to be driven thereby, means for stopping the rotation of each wheel, electromagnets for actuating said means, and means for determining the relative movement of said wheels in time units. 70

5. In a timing device, a shaft, a constant speed motor for driving said shaft, a plurality of wheels frictionally mounted upon said shaft so as to be driven thereby, pawls for stopping the rotation of said wheels, 75 means responsive to changes in an electric circuit for actuating said pawls, and means for determining the relative rotation of said wheels.

6. In a timing device, a pair of rotatable 80 members, means for driving said members at a uniform speed, means for stopping said members at different times, a dial carried by one of said members, and a pointer carried by the other of said members and movable over said dial to indicate directly 85 relative movement between said members.

In witness whereof, I have hereunto set my hand this 29th day of January, 1920.

HENRY E. WARREN.
